UNITED STATES PATENT OFFICE

2,327,512

ROTARY GAS BURNER

Edwin L. Dennis, Reserve, La.

Application September 30, 1939, Serial No. 297,231

1 Claim. (Cl. 158—118)

The present invention relates to a burner for natural gas or other gaseous fuel supplied under pressure, such as atomized oil mixed with steam.

In the copending application of Dennis, the present inventor, Serial No. 88,045, filed June 29, 1936, for Rotary gas burner, now Patent No. 2,177,245, dated October 24, 1939, is disclosed a rotating gas discharging device, whose rotation, preferably produced by the fuel itself, not only obtains the delivery for admixture with the gas of the proper amount of combustion supporting air, but also causes a mechanical mixture of the gas and air so complete as to assure substantially instantaneous and complete combustion of the gas in the apparatus in which the gas is burned. Where the rotation of the gas discharging and distributing device is dependent upon the pressure of the fuel itself, it is essential that the pressure be maintained at more than a predetermined minimum below which the pressure of the gas is not sufficient to assure a satisfactory rotation of the gas distributor. The principal object of the invention is to provide for a rotation of the gas distributor from an external source, thereby making it possible to use gas for fuel where the pressure on the gas is only sufficient to assure a discharge of gas through the nozzles of the gas distributor but not necessarily sufficient to provide for a rotation of the discharging device.

In accordance with the present invention the rotary gas distributor which assures a uniform distribution of the gas over substantially the entire cross-sectional area of the air stream so that the resultant flame as the gas and air burns is of uniform intensity throughout is driven by an external source of power which may be, for example, an electric motor connected to the gas distributor or a fan associated with the distributor and driven by the passage of air for combustion through the burner. By the use of an external source of power for driving the gas distributor, the rotation of the distributor is assured independently of the gas pressure, thereby also assuring a thorough mixing of the gas and air for complete combustion.

Other and further objects and advantages of the invention will more fully appear from the following detailed description taken in connection with the accompanying drawings in which—

Fig. 1 is a sectional view through a device embodying the invention.

Fig. 2 is a sectional view through a modified form of the invention.

Fig. 3 is a fragmentary view of a device, showing another modification.

With reference first to Fig. 1, the casing 1 in which the rotary distributor, designated as a whole by the numeral 2, is mounted, communicates at its inner or left hand end, with the combustion space, not shown, of a furnace or other apparatus in which the gaseous mixture is burned. Air for combustion is admitted at the outer or right hand end of the casing, which may be provided, as shown, with a draft regulator, comprising a stationary disk 3 held to the casing by bolts 4 and a slide 5 overlying the disk 3. The slide has openings 6 which may be moved more or less into alignment with corresponding openings 7 in the disk 3, the slide being held in adjusted position by a locking nut 8.

Within the casing 1 is positioned a spider 10 in which is journaled on suitable anti-friction bearings 11 a hollow shaft 12. On the inner or left hand end of the shaft is secured a fan 13 which is a part of the rotary element 2. The latter also comprises the gas-distributor proper 14 having hollow apertured arms 14a, which is secured to the hub of the fan and itself has a hollow hub 15 with which the hollow shaft 12 communicates.

A shaft 16 extends through the hollow shaft 12 and is secured thereto by radially extending webs 17. The shaft 16 extends to the right beyond the end of a cap 18 which is secured to the spider 10, and has mounted thereon a pulley 19. This pulley is connected by a belt 20 to a pulley 21 on a suitable driving motor 22. By this arrangement the fan 13 and gas distributor 14 are positively driven from the motor independently of the discharge of gas from the distributor, and thus rotation of the distributor is assured even when the pressure on the gas entering the distributor is so low that the reaction of the gas on the arms 14a of the distributor as it escapes through openings 14b therein is not sufficient by itself to cause a rotation of the distributor and fan. Passages 14c in the arms 14a communicate with the hollow hub of the distributor 14 and thereby direct gas to the openings 14b, gaseous fuel being supplied to the hollow hub, as will hereinafter appear.

By this arrangement it is possible to use gas at an extremely low pressure with the rotation of the distributor providing for a uniform and thorough distribution of the gas over the entire area of the passage through the casing 1 and also a thorough mixing of the gas with air forced through the casing by the fan 13. This mixture of gas and air is so complete as to assure almost

perfect combustion of the gas in the furnace, and is controlled by the number and spacing of the openings 14b as will be apparent.

In some burner installations there is already available a blower or other means for supplying air to the furnace and in this event a structure of the type shown in Fig. 2 may be utilized. With reference to this figure, the casing, not shown, has its rotary member 2' mounted on the end of a hollow shaft 12'. The latter is journaled in a spider 10' connected to the casing.

The rotary member 2' consists of the distributor 14' having radially extending arms with openings therein, as shown, similar to the distributor 14. The distributor is rotated by a shaft 16' positioned within the hollow shaft 12', and secured thereto by radially extending webs 17'. A motor, as in Fig. 1, drives this shaft through suitable pulleys and belt and thus provides a positive rotation of the gas distributor. Air supplied from an external source under a low pressure enters the casing at the right hand end thereof and is thoroughly mixed with gas discharging from the openings in the distributor 14' so that the mixture of gas and air entering the furnace will be proper for complete combustion.

In each of Figs. 1 and 2, the gas distributor is positively rotated by a positive driving means for complete mixture of the gas and air and for a uniform distribution of the gas over the entire cross-sectional area of the air passage in which the distributor arms turn. It is also possible where air under slight pressure is provided from an external source to have the gas distributor rotated in response to the movement of the air past the distributor. To this end, as shown in Fig. 3, the arms of the gas distributor 14" are provided with integral fan blades 23 upon which air passing through the casing 11" impinges to cause a rotation of the distributor. In this arrangement the distributor 14" is supported on a shaft 12" in a spider 10" which is in turn suitably supported centrally of a casing similar to that of Fig. 1. Fan blades 23 are positioned on the distributor 14" to obtain the desired rota-

tion of the distributor, dependent upon the rate of air travel through the casing.

It will be understood that gas is directed to the distributor 14 through an inlet 24 in the cap 13, Fig. 1, and through the hollow shaft 12. Suitable seals or gaskets prevent escape of the gas into the bearings. The shaft 12 communicates with the hollow hub of the distributor and the channels or passages 14c in the arms direct the gaseous fuel to the discharge openings 14b, as shown.

From the foregoing it will be apparent that the present invention provides for a positive rotation of the gas distributor when the gas pressure is not sufficient to assure a rotation of the distributor by the reaction of the discharge of the gas through the openings in the rotary member. Thus, in Figs. 1 and 2, the positive rotation is provided by an electric motor or other suitable source which drives the gas distributor; in Fig. 20, the movement of air through the casing in which the distributor is located provides for the rotation of the distributor.

I claim,

In a burner for gaseous fuel, a hollow casing 25 providing a passage for air, a spider in said casing having a stationary hollow hub, a hollow shaft journaled in said hub and extending beyond the hub to the outlet end of said casing, a hollow gas distributing device secured to the extended end 30 of said hollow shaft and communicating therewith, said distributing device providing gas discharging apertures extending across substantially the entire active area of said air passage, the other end of said hollow shaft being provided 35 with a gaseous fuel inlet opening, a driving shaft arranged within said hollow shaft and connected thereto at the latter's opposite ends, said driving shaft having a portion extending from the inlet end of said casing, and a driving motor mounted 40 exteriorly of said casing and having a driving connection with said driving shaft to rotate the latter and thereby drive said gas distributor.

EDWIN L. DENNIS.
